E. SCHWARTZ.
ELECTRIC SOLDERING IRON.
APPLICATION FILED FEB. 14, 1918.

1,288,444.

Patented Dec. 17, 1913.

Inventor:

Horn and Sonne Atty's.

UNITED STATES PATENT OFFICE.

EDWARD SCHWARTZ, OF NEW YORK, N. Y., ASSIGNOR TO MANHATTAN ELECTRICAL SUPPLY COMPANY, OF NEW YORK, N. Y., A CORPORATION OF NEW JERSEY.

ELECTRIC SOLDERING-IRON.

1,288,444.

Specification of Letters Patent. Patented Dec. 17, 1918.

Application filed February 14, 1918. Serial No. 217,166.

To all whom it may concern:

Be it known that I, EDWARD SCHWARTZ, a citizen of the United States of America, residing at New York, in the county and State of New York, have invented a certain new and useful Improvement in Electric Soldering-Irons, of which the following is a specification.

My invention relates to electric soldering irons and the object of my invention is to provide an improved construction for tools of this type, the particular features of which are set forth in the following specification and claim and in the accompanying drawings, in which—

Figure 1 is a longitudinal section through a soldering iron in which my invention is embodied in one form.

Fig. 2 is a transverse section on the line 2—2, Fig. 1;

Fig. 3 is a partial longitudinal section on the line 3—3, Fig. 2; and

Fig. 4 is a transverse section on the line 4—4, Fig. 1.

The construction here illustrated comprises a soldering point 10, shouldered at 11 to form a seat for the tubular casing 12 secured thereto by a set screw 13. A reduced shank 14 extends some distance into the casing and affords an annular space between its periphery and the casing to receive the metallic sheath or spool 15, the short flange 16 at one end of which abuts against the shoulder 17. A resistance coil 18 is wound upon the sheath 15 and insulated therefrom by any suitable means. I have found most suitable for this purpose a thin sheet of mica, which is not only an electrical insulator, but also a good conductor of heat. After the resistance coil 18 is wound thereon, its spires may be spaced apart and insulated by an insulating cement applied as a wash. A second thin sheet of mica (optional) may then be wrapped around the coil and a final wash of the cement applied to hold all rigid. Inasmuch as the cement is a relatively poor heat conductor, this has the effect of not only keeping the casing 12 cool at this point, but also forcing the heat from the coil inward to the core 14 where it is wanted.

At one end, the sheath 15 is pierced to afford ingress and egress for the leads to and from the coil. To insulate these leads 19 and 20 and hold them in spaced relation against short circuit, I provide an insulating

plug 21, the ends of which enter the holes in the sheath and which is itself provided with passages opening through the ends of the plug to receive the leads. The latter may be connected in any suitable way to the source of current. I have here shown them soldered at 22 to wires 23 and 24 passing through a spacing block 25 of insulation and insulating casings 26 and 27 to a terminal block 28 of insulating material, secured by a cross pin 29 to the opposite end of the casing 12. Passages 30 and 31 extending longitudinally through the insulating block 28 open to the ledges 32 and 33 on which are mounted the binding posts 34 and 35 by which the wires 23 and 24 may be connected to the terminals of the power cable (not shown). The manner of connection to the power cable is, of course, immaterial, and instead of the binding screws 34 and 35, I may employ receptacle terminals to cooperate with the jacks of an attachment plug at the end of the power cable in well understood manner.

The tool is held during use by a handle 36, preferably of wood or of other material of low heat conductivity, into the bore of which the casing 12 extends and to which it is readily attached by means of a ferrule 37 which screws onto a threaded ring 38 secured to the exterior of the casing.

It will appear from the above description that the tool comprises relatively few parts and that each of these parts is self-contained so that upon injury to or exhaustion of any of said parts it may be replaced without difficulty and without discarding the entire tool. Thus a new point 10 may be substituted by merely removing the set screw 13, withdrawing the old point and inserting the new one in its place. In case of injury to the heating unit, the sheath 15 carrying the resistance coil may be removed bodily and a new coil substituted. In case of breakage of the handle 36, the latter is readily replaced by a new one screwing onto the ring 38 in like manner. Should the casing 12 become damaged, it may be readily replaced by disconnecting the wires from the binding screws 34 and 35 so that the insulating block 28 may be drawn off with the casing. It will be noted further that the casing 12 comprises a one-piece tube, one end of which abuts against the shoulder 11 on the copper point, while

the other end is drawn down to a stem of less diameter adapted to enter the bore of a handle 36 of convenient size. The parts of the device may be readily manufactured at relatively low expense and they may be expeditiously assembled.

Various modifications in details of construction will readily occur to those skilled in the art, which do not depart from what I claim as my invention.

I claim:—

An electric soldering iron having a soldering point with rearwardly-extending, integral shank of slightly reduced diameter, a metallic spool sleeving on said shank, a resistance coil wound on said spool, a plug of insulation in the end of said spool through which the coil ends pass, a solid, tubular

casing surrounding said spool and coil and abutting against the soldering point and extending, with reduced diameter, toward the opposite end of the tool, a plug of insulation in the reduced end of said casing, wire terminals mounted on said plug in the reduced casing end and wire leads passing therefrom through this plug and casing to the coil terminals at the plug in the spool end, together with a handle of low heat conductivity mounted on the end of said reduced stem of the casing and inclosing the wire terminal plug, substantially as described.

In testimony whereof I have signed my name to this specification.

EDWARD SCHWARTZ.
